UNITED STATES PATENT OFFICE.

LE GRAND SKINNER AND EDWIN F. WILLIAMS, OF ERIE, PENNSYLVANIA, ASSIGNEES
TO SKINNER ENGINE COMPANY, OF ERIE, PENNSYLVANIA, A CORPORATION OF
PENNSYLVANIA.

STEAM-ENGINE.

1,033,280

Specification of Letters Patent.

Patented July 23, 1912.

Application filed September 30, 1911. Serial No. 652,086.

To all whom it may concern:

Be it known that we, LE GRAND SKINNER and EDWIN F. WILLIAMS, citizens of the United States, residing at Erie, in the 5 county of Erie and State of Pennsylvania, have jointly invented certain new and useful Improvements in Steam-Engines; and we do hereby declare the following to be a full, clear, and exact description of the invention, such as will enable others skilled in the art to which it appertains to make and use the same, reference being had to the accompanying drawings, and to the letters of reference marked thereon, forming part of 10 this specification.

This invention relates to improvements in steam-engines of the type in which the working steam enters the cylinder at the ends thereof and exhausts through ports at 20 the center of the cylinder which are uncovered by the piston at and near the end of its working stroke, and it consists substantially in providing the cylinder with main exhaust ports between the ends of the cylinder and the central exhaust ports therein, located at points approximately thirty percent. of the length of the working stroke of the piston from the ends of the cylinder, and valves for said main exhaust ports operating to open said ports after the central exhaust port is opened and close said ports after the piston has covered them on its return stroke and thereby heavy pressures on the main exhaust valves during their operation are eliminated. 30

The objects and advantages of this improvement are as follows, viz: that comparatively small clearances are required at the ends of the cylinder, as during the return stroke of the piston the steam continuously exhausts through the main exhaust ports, until they are covered by the piston on its return stroke, and only the steam remaining in the cylinder between the main exhaust ports and the end of the cylinder is utilized to provide the compression necessary to fill the small clearances remaining when the return stroke of the piston is completed. 40

Another result of this construction is the thermal advantage gained from exhausting the comparatively cool expanded steam without passing it over the heated ends of the cylinder. 50

A further object and advantage of this

invention is, that by the use of main exhaust ports located as hereinbefore described the engine is more economical in the use of steam, and develops more power, than an engine having only a central exhaust, as 60 will be hereinafter set forth and diagrammatically demonstrated and explained.

A further object and advantage of this invention is that an engine so constructed can be utilized with equal facility as a non-condensing engine, as well as a condensing engine, it only being necessary in the latter case to disconnect the mechanism which operates the main exhaust valves, so that they will remain inoperative. 70

These and other features of this invention are hereinafter fully set forth and explained and illustrated in the accompanying drawings, in which:

Figure 1 is a vertical central section on the line $x-x$ in Fig. 2 of a steam engine cylinder embodying this invention. Fig. 2 is a transverse section of the same on the line $y-y$ in Fig. 1, showing one of the valves of the main exhaust ports in closed position. Fig. 3 is a detail showing one of the main exhaust valves in open position. Fig. 4 is a detail showing a top or plan view of one of the main exhaust valves. 75

In these drawings A, indicates a steam engine cylinder, B, inlet ports at the ends of the cylinder controlled by inlet valves B', operated by convenient valve-gear (not shown). The cylinder A, is provided with the usual reciprocating piston C, and with central exhaust ports A', adapted to be uncovered by the end of the piston C, at and near the end of its stroke, which ports A', open into an annular exhaust chamber A², which communicates with a longitudinal exhaust chamber A³, in the lower part of the cylinder body, from whence the exhaust passes out through the exhaust pipe A⁴. In the bottom of the cylinder A between the ends of the cylinder, and the central exhaust ports A', there are main exhaust ports D, located approximately thirty percent. of the length of the working stroke of the piston from the ends of the cylinder. These main exhaust ports are provided preferably with mechanically operated valves D', preferably of the slide-valve type. For operating these main valves we provide convenient valve-gear E E' which communicates with and is operated by ordinary valve-gear mecha- 85 90 95 100 105 110

nism (not shown). The valve-gear E E' preferably communicating with the valves D' by means of cam-slots e, engaging rollers d', on the valve-stem d, of said valves, 5 whereby an intermittent motion is given to the valves D'.

The preferred construction of the valves D', and their valve-seats D², is cylindrical in form and contour, as illustrated in Fig. 10 4, so that the valve D', and its seats D², will removably fit into cylindrical chambers F, in the lower part of the cylinder A. The valve-seats D², are also provided 15 with transverse exhaust passages d², d², communicating (when the valve-seats are in place in the chambers F) with the ends of the exhaust chamber A².

In Fig. 1 of the drawings are shown relief or drainage valves G, G', which may be 20 opened or closed by operating the hand wheels G' G', whereby should water accumulate in the cylinder while it is standing cold, the same may be drained away if desired.

25 In operation the valves D', are normally closed as illustrated in Fig. 2, during the working traverse of the piston C, and until the piston uncovers the central ports A', when the valve D', in the end of the cylinder 30 being traversed by the return stroke of the piston is opened and the steam then exhausts through the main exhaust ports D, into the exhaust chamber A², and the valve D', remains open until the auxiliary ports 35 D, are covered by the piston C, when the valve D', is closed and remains closed during the working stroke of the piston.

The advantages and results of the location 40 and operation of the main exhaust ports D, in conjunction with the central exhaust ports A', is economy in steam consumption, increased efficiency therefrom, and thermal advantage from exhausting the cool steam without contact with the heated end portions 45 of the cylinder, and the comparatively small clearance required.

It will be manifest to those skilled in the art that while the main exhaust ports and valves have been hereinbefore shown and 50 described as being located approximately thirty percent. of the stroke from each end of the cylinder, that considerable variation in the location of said ports and valves from that shown and described herein may exist 55 without departing from the spirit of our invention.

Therefore having described our invention so as to enable others to construct and utilize the same, what we claim as new and desire to secure by Letters-Patent is:

60

1. The combination with a steam engine cylinder having a central exhaust port, and main exhaust ports between each end of the cylinder and said central exhaust ports, of valves for opening and closing said main 65 exhaust ports, and valve-gear adapted to mechanically open and close said valves at periods when said valves are free from pressure substantially as set forth.

2. The combination in a steam engine, of 70 a cylinder having a central exhaust port, and main exhaust ports located between said central exhaust and each end of the cylinder, a piston adapted to uncover the central exhaust port at and near the end of its working stroke and to cover the main exhaust ports during the first part of its working stroke and the latter part of its return stroke, valves for said main exhaust ports, and valve gear adapted to open said valves 75 after the central exhaust is opened and close them after the main exhaust ports are covered by the piston on its return stroke, substantially as set forth.

3. The combination in a steam engine, of 80 a cylinder having inlet ports at its ends, central exhaust ports and main exhaust ports located between said central exhaust port and each end of the cylinder, valves and valve-gear for controlling said inlet ports, 85 a piston operating to uncover the central exhaust ports at and near the end of its working stroke and to cover the main exhaust ports during the first part of its working stroke and the latter part of its return 90 stroke, valves for opening and closing the main exhaust ports, and valve-gear operating to open the main exhaust ports after the central exhaust ports are opened and retain them open until the return stroke of 100 the piston covers the main exhaust ports, and then close said valves and retain them closed until the central exhaust ports are again opened, substantially as set forth.

In testimony whereof we affix our signatures, in presence of two witnesses.

LE GRAND SKINNER.
EDWIN F. WILLIAMS.
